ARCHIBALD E. SUTLIFF, OF SYRACUSE, NEW YORK, ASSIGNOR TO SARGENT & COMPANY, OF NEW HAVEN, CONNECTICUT, A CORPORATION OF CONNECTICUT.

KEY-CUTTING MACHINE

1,156,642.

Specification of Letters Patent.

Patented Oct. 12, 1915.

Application filed November 3, 1913, Serial No. 798,909. Renewed December 31, 1914. Serial No. 879,959.

To all whom it may concern:

Be it known that I, ARCHIBALD E. SUTLIFF, a citizen of the United States, and a resident of Syracuse, in the county of Onondaga 5 and State of New York, have invented a new and useful Key-Cutting Machine, of which the following is a full, clear, and exact description.

This invention relates to special metal 10 working machinery and has particular reference to means for quickly and accurately cutting or shaping keys for door locks or the like.

Among the objects of the invention is to 15 produce a machine operated or controlled by hand, whereby the manager or superintendent of a building, for example, having a number of locks, may easily and readily keep such locks supplied with keys.

20 A further object of the invention is to produce a cutting machine for the making of keys whereby the notches are not only easily and quickly cut but are formed with their bottoms on arcs of circles drawn from 25 the center of the shank or axis of rotation of the key, whereby the key is rendered easier of operation than when formed by the usual process and also prevents damage to the lock by breakage or abrasion.

30 A still further object of the invention is to provide a machine of the class set forth having an arbor to which are detachably clamped any desired arrangement or combination of circular saws for the formation 35 of a key having notches of a depth corresponding to the specification of the particular lock to be fitted.

The foregoing and other objects of the 40 invention will hereinafter be more fully described and claimed and illustrated in the drawings forming a part of this specification in which like characters of reference indicate corresponding parts in all the views, and in which—

45 Figure 1 is a plan view of a preferred embodiment of this invention; Fig. 2 is a diagram illustrating the relation of the key bit to the path of the saw teeth; Fig. 3 is a vertical section on the line 3—3 of Fig. 1; 50 Fig. 4 is a broken plan view illustrating the position of the key and the manner of holding it in place on the bed plate; Fig. 5 is a vertical transverse section on the line 5—5

of Fig. 1; Fig. 6 is a vertical section corresponding to Fig. 3 but indicating a variation in use of the machine; Fig. 7 is a detailed plan view of the bed plate for supporting the key while sawing the grooves; Fig. 8 is a corresponding view of the upper member of the key holding clamp; and Fig. 60 9 is a diagrammatic view of a modification of means for operating the key while being cut.

The several parts of the device may be made of any suitable materials, and the 65 relative sizes and proportions, as well as the general design of the mechanism, may be varied to a considerable extent without departing from the spirit of the invention hereinafter more fully set forth and specifically claimed.

At 10 I show a rigid supporting base adapted to be secured in place firmly as upon a bench or the like and journaled in 70 definite position thereon is a horizontal shaft 11, bearings 12 of any suitable nature being employed for supporting it. At one end of said shaft is secured a means for 75 rotating the shaft, such means being indicated by way of illustration as a crank 13. 80 It will be understood, however, that any suitable driving means may be employed for this purpose. At the other end of the shaft is arranged a cutting head 14 comprising a 85 series of disks or circular cutters 15 and blanks 16. These disks are secured detachably to the arbor by means of clamping plates 17 secured in place by means of a nut 18. While I show the use of three circular saws and two blank disks 16, I wish it to be 90 understood that this illustration may be subject to variation in accordance with the specification or scheme of the locks pertaining to any building or system for which the machine is adapted. More specifically, the 95 common practice is for the house to be provided with a key scheme or schedule describing a lock for each room with reference particularly to the number and depth of the notches in the key bit adapted to fit such 100 particular lock. It being well known that hotel guests very frequently take with them the keys belonging to the rooms occupied by them and it being also well known that the manager of such hotel is required to keep 105 the door locks fitted with keys for the use

of succeeding guests, it follows that much trouble and expense are caused from the loss of keys in the manner just stated.

Associated with the base 10 of the machine 5 is a bed plate 19, shown best in Fig. 5, including an anchor 20 abutting against the main portion of the base 10 and beneath the top 10' of the same. Said bed plate therefore occupies a definite position with respect 10 to the base and the power shaft 11. This position is maintained at the end opposite the anchor 20 by means of a wedge 21 extending through a hole 19' in the bed plate and engaging against one edge of the top of 15 the base 10. Said bed plate has secured to it a key holding clamp comprising upper and lower members 22 and 23. The member 23 is preferably secured permanently to the bed plate 19 and is provided with a 20 transverse groove 23' to receive a shank 24 of the key.

The bit 25 of the key is adapted to project upwardly through the slot 26 in the upper clamp plate 22, said member 22 also 25 having a groove 22' registering with the lower groove 23' whereby the key is held in definite position with respect to its axis. In other words, the axis of the key is held in fixed position but the key itself is adapted 30 to rotate through an angle of approximately 90 degrees around such axis, as shown in Figs. 2 and 4, while being cut, the slot 26 being wide enough in one direction to just receive the bit of the key whereby the key 35 is held in definite position longitudinally of its axis and is wide enough in the other direction to permit the desired rotation of the key. The upper clamp member 22 is secured detachably in place upon the lower member 40 by means of any suitable quick-acting device herein typified by a screw 27. It will be seen, therefore, that with the bed plate secured in definite position with respect to the base and with the clamp members 22 45 and 23 secured likewise in definite position upon the bed plate, the key locked within the grooves 22' and 23' with its bit 25 projecting upwardly through the slot 26 will always bear a definite relation to the cutters 50 15, and the cutters are so arranged as to vary in diameter in accordance with the respective depths of notches of the key bit.

Any suitable means may be employed to 55 rotate the key around its axis while the bit notches are being cut, and for this purpose I provide a lever 28 having a notch 29 at its lower end for engagement with the hilt 30 of the key. As a convenient and reliable 60 means for manipulating the lever 28 so as to move the key gradually around its axis, I connect the upper or outer end of the lever to a spindle 31. Said spindle is provided with a knob 32 as a convenient means for rotating it within the end of the lever. A 65 pinion 33 is arranged for engagement with

a fixed arc-shaped rack 34 having its center concentric with the axis of the key and secured at its bottom to the base 10. The pinion 33 is provided with a flange 35 whereby it is guided along the rack. By the operator 70 turning the knob 32 the pinion is caused to advance slowly along the rack and thereby feed the lever slowly around the axis of the key, causing the key to turn as shown in Fig. 2 and bringing the bit of the key into 75 engaging position with respect to the circular saws 15. The bottoms of the notches, therefore, that are cut by the saws will be rounded or convex with reference to the axis of the key, the center of curvature coinciding with the axis of the key. It follows that since the feeding of the key into coöperation with the saws may be performed gradually and slowly, the key bit is not only cut but smoothly finished by such saws all in a 80 simple and comparatively quick operation. The spindle 31 extends through a slot 29' of the lever 28 whereby the lever may be given a certain longitudinal movement independently of the means for actuating the lever. 90

From the description of the mechanism above given it will be understood that in order to make a key for a certain specified lock according to the scheme of the building, the cutters 15 or any number of them 95 are selected and arranged by number according to the arrangement or depth of the notches to be formed in the key bit. These cutters are then secured in place in the manner described. The key blank of standard form or size is then secured in place in the clamp 22, 23, and the lever 28 and actuator for controlling it are caused to move the key around its axis and the key will be quickly finished so far as the notches are 100 concerned. 105

After the notches are cut it is necessary to cut one or more grooves longitudinally along the sides or faces of the bit, and this is accomplished in the same machine by 110 the use of a groove cutter 36 clamped to the same shaft 11. Said cutter may be single, double, or any other form according to the arrangement of the grooves to be cut, and the key for this purpose is clamped in a movable bed plate 19^a to which is secured a clamp comprising members 22^a and 23^a having the same general relation to the bed plate as the corresponding clamp members above described, but adapted to hold the key in a substantially flat position and at right angles to the manner of holding when the bit notches are being cut. More specifically, the clamp member 23^a is in the nature of a matrix having a seat 23^b to fit and receive the key blank, as shown in Figs. 6 and 7, the upper portion of the blank extending above the upper surface of the member 23^a. The upper member 22^a is provided with a slot 22^b 115 above the key bit through which the cutter 120

125

36 extends for the purpose of cutting the groove or grooves while the bed plate 19^a is pushed longitudinally by hand or other means. It will be understood also that the 5 groove cutting devices for the key will be arranged so as to accommodate the grooving on either or both sides of the bit.

The modification of Fig. 9 contemplates the employment of a gear or gear segment 10 28' which, instead of the lever 28, is adapted to control the position of the key as to its movements around its axis, said gear segment being mounted for partial rotation around the axis of the key. A pinion 33' is 15 mounted upon a fixed axis 34' and meshes with the gear segment 28' whereby, when the pinion is rotated by the knob 32, the key will be caused to move around its axis substantially the same as above described in connection with Figs. 3 and 5.

It will be understood from the foregoing description that by my new method of cutting the notches in the edges of key blanks, the cutting disk or other notch-forming 25 member first begins to cut or abrade the blank at what may be termed a corner thereof, where two surfaces meet each other substantially at right angles. In other words, the cutter cuts away one side 30 face of the blank, and simultaneously cuts away the narrow surface or edge of the blank. Then, as the operation continues, the cutting or abrading action is carried across the narrow surface or edge of the 35 blank, and notches the blank almost as deeply at the other side face as at the first side face. Then as the operation is further continued, the cutter continues to pass through the notch so that on the second side 40 face of the bit to be cut away, the notch is deepened to the same extent as at the first side face. The result is that the notching of the bit is considerably facilitated, and the bottom of the notch will have a convex 45 curvature on an arc drawn approximately from the center of the key axis, as previously described. In the broad aspects of the invention, it is obviously unessential that the axis of rotation of the notch-forming 50 element be stationary, and that the key be movable relative to said element. Obviously, the arrangement could be reversed by making the cutter or notch-forming element movable with respect to the key, without departing from the broad principle of 55 the invention. In either case the movable part moves or turns about the axis of the key as a center. Various changes in other particulars may also be made without 60 departing from the scope of the claims.

Having thus described my invention, I claim as new and desire to secure by Letters Patent:—

1. In a key cutting machine, the combination of a base, means to secure a key in

definite position upon the base, said securing means permitting, however, a certain amount of rotation of the key around its axis, a rotary cutting device journaled in fixed position upon the base and adapted to act upon 70 the key bit, and an actuator serving to rotate the key around its axis while the bit is being cut by the cutting device.

2. The combination of a base, a key clamping device having definite position with respect to the base and including relatively fixed and removable members having registering key shank grooves, the removable member having a slot through which the key bit is adapted to project upwardly, a 75 rotary cutting device, means to rotate the cutting device and maintain the same in definite position with respect to the key clamping devices, and a hand controlled actuator serving to rotate the key slowly and 80 gradually while being cut.

3. In a key cutting device, the combination of a base, a rotary cutting device journaled upon the base, means to operate the cutting device, a key clamping device adjacent the cutting device serving to hold a key in definite axial position with respect to the cutting device, and a hand controlled actuator serving to rotate the key while being 85 cut, said actuator including an arc-shaped 90 rack having its center coaxial with the key, and means operating over said rack and having loose engagement with the hilt of the key.

4. In a key cutting machine, the combination of means to secure a key with its axis in fixed position, rotary cutting devices co-operating with the key bit, and means to rotate the key around its fixed axis while being cut by said cutting devices, whereby 100 the cut surfaces are formed on arcs having 105 centers coincident with the axis of the key.

5. A key cutting machine comprising a base, a shaft journaled on said base and carrying a cutter, means for holding a part 110 of the key in fixed relation to the base, and means for swinging the key with respect to said cutter, while it is being cut thereby; substantially as described.

6. The combination of a base, means to 115 clamp a key to the base with the axis of said key in a fixed position relative to the base, a cutter mounted on the base, and means for moving the key on its axis relative to said cutter; substantially as described.

7. The herein-described key cutting machine comprising a base, a bed plate associated with the base and arranged transversely thereof, a shaft extending longitudinally of the base, and over the bed plate, a 120 cutter on said shaft over the bed plate, and means to clamp the key in a fixed position on the bed plate, in which it is secured against bodily movement relative to the bed plate and base, said key being rotatable into 125 130

- engagement with said cutter; substantially as described.
8. In a key cutting machine, the combination of a base, means to secure a key in definite position on the base, said securing means permitting, however, a certain amount of rotation of the key around its axis, and a cutting device on the base adapted to act upon the key bit; substantially as described.
- 10 9. In a key cutting machine, the combination of means to secure a key with its axis in a fixed position, and a rotary cutting device supported in proximity to the key bit, such key being rotatable about its axis, while being cut by said cutting device; substantially as described.
- 10 10. In a key cutting machine, the combination of means to secure the key in a definite position, and means to form in the edge 20 of the key bit a notch having a convex bottom, the curvature of which corresponds substantially to an arc concentric with the key axis; substantially as described.
11. In a key cutting machine, the combination of a rotary cutting device, and means to rotate a key around its own axis while being cut by said device; substantially as described.
12. In a key cutting machine, the combination of a cutter, adapted to cut a key, and means mounting one of said members mov- 30
- ably with respect to the other, so that it can turn about the axis of the key as a center; substantially as described.
13. In a key cutting machine, the combination of a rotary cutter having a peripheral cutting surface, for cutting a key, and means for mounting one of said members so that it can swing about the key axis during the cutting operation; substantially as de- 40
14. In a key cutting machine, the combination of a rotary cutter, adapted to cut a key, and means for mounting the key so that it can swing on its axis into engagement with 45 said cutter; substantially as described.
15. In a key cutting machine, the combination of a rotary cutter having a peripheral cutting edge for cutting a notch in a key, means for fixedly mounting one of said members, and means mounting the other of said members so that it can swing about the longitudinal axis of the key as a center during the notching operation; substantially as 50
- 55 described.

In testimony whereof I have signed my name to this specification in the presence of two subscribing witnesses.

ARCHIBALD E. SUTLIFF.
